eral Motors Corporation, a corporation of Dela-
ware

Application January 31, 1931, Serial No. 512,633
Renewed May 26, 1937

17 Claims. (Cl. 230—147)

This invention relates to refrigerating apparatus of the compression type and more particularly to motor-compressor units for use with refrigerating apparatus of such type.

One of the objects of the present invention is to provide an improved compressing apparatus which is inexpensive to manufacture, economical to operate and easily assembled.

Another object is to provide an improved compressing means of the oscillating ring type having a plurality of compression spaces, and to provide means for sealing said compression spaces from one another, which means also seals the intake from the discharge sides of said compressing means.

Another object is to provide an eccentric oscillating ring type compressing means with counter-balancing means to lessen vibrations.

Another object is to provide improved means for loading and unloading the compressing means.

Further objects and advantages of the present invention will be apparent from the following description, reference being had to the accompanying drawings, wherein a preferred form of the present invention is clearly shown.

In the drawings:

Fig. 1 is a top plan view, partly in elevation and partly broken away, of a compressing apparatus embodying features of the invention;

Fig. 2 is a view of a refrigerating system embodying features of the invention showing the system partly diagrammatic and an enlarged view in cross-section of the compressing apparatus shown in Fig. 1, the view of the compressing apparatus being taken along the line 2—2 of Fig. 1;

Fig. 3 is a view in cross-section of a portion of the compressing apparatus shown in Fig. 2, the view being taken in the direction of the arrows 3—3 of Fig. 2;

Fig. 4 is a view similar to Fig. 3 and showing a modified form of sealing means for the compressing apparatus; and

Fig. 5 is a fragmentary view of a portion of the compressing apparatus shown in Fig. 1 and showing a side-view in elevation of the discharge valve mechanism.

Referring to the drawings, the numeral 20 designates in general a refrigerating system which includes therein a motor-compressor unit 22, condenser 24 and cooling or evaporator element 26. The motor-compressor unit herein shown is of the type in which both the motor and compressor are enclosed within a fluid-tight, her-

metically sealed casing. However, it is to be understood that the invention is not limited to such a compressing unit. The compressing unit 22 comprises motor 30 which includes rotor 33 and stator 35, and a compressing means 37 actuated by motor 30. The compressing unit withdraws gaseous refrigerant from the evaporator through a vapor conduit 42, compresses the gaseous refrigerant and delivers it to the condenser wherein it is liquefied and from which it is delivered to a receiver 43 which is connected to the evaporator by means of a supply conduit 45 under the control of an expansion valve 46. The compressing means 37 is shown as driven by the electric motor 30 and the starting and stopping of the motor is controlled by an automatic switch 47 controlled by a thermostat bulb 48 in the vicinity of the evaporator 26.

The motor-compressor unit 22 is enclosed within the fluid-tight casing 40 which includes an upper cover 50, and an intermediate member 52 and a lower member 54 suitably clamped together by screws 55 and 56. The lower member 54 and the intermediate member 52 cooperate to form a reservoir 57 for a body of lubricating oil preferably mineral oil. The intermediate member 52 serves also to provide an intake chamber 59, which is provided with a check valve 60 located at the inlet thereof to permit refrigerant to enter said chamber but preventing return thereof. The intermediate member 52 is provided with a horizontal web or plate 62 at the top thereof which serves to divide the casing 40 into two separate chambers for compressed fluid, namely, 65 and 66. Both chambers are located on the same side of the compressor, and for instance, on the high pressure side as shown in the drawings. The web 62 is provided with an annular groove 70 which provides a compression chamber for the compressing means 37.

The compressing means 37 is of the oscillating ring type which is one of the types which must be flooded with a lubricant to accomplish any appreciable compressing action as a gaseous medium as described hereinafter. The compressing means includes a disc-shaped member 72 which forms the top wall of the compression chamber 70. The member 72 is provided with a downwardly depending ring 74 which oscillates within the compression chamber for compressing the fluid therein. The ring 74 is so positioned within the chamber 70 so as to provide a plurality of compression spaces within the compression chamber 70. As shown in Fig. 3 it will be noted that a compression space is provided adjacent 55

the outer periphery of said ring and a second compression space is provided adjacent the inner periphery of said ring. Thus it will be noted that there is provided a compression space adjacent 5 each periphery of the ring 74 as shown in Fig. 3 where one compression space is indicated at 75 and a second compression space is indicated at 16. Each of the compression spaces is provided with a separate discharge valve 71. Compression 10 abutments are provided in the form of an oscillating or rocking pin 80 disposed within the compression chamber 70 to seal one compression space from the other and arranged so as to be in engagement with at least one of the ends of the 15 ring during pumping operation so as to prevent leakage from one compression space to the other. The oscillating pin as shown in Fig. 3 is disposed within the chamber 70 with its ends in slidable engagement with opposite vertical walls of the 20 annular groove or compression chamber 70. During the operation of the compressing means the pin 80 oscillates with its ends slidably engaging the walls of the compression chamber 70 while the ring member 74 oscillates within the 25 compression chamber 70 with respect to the axis of the pin 80. Throughout operation of the compressing means there is a plane contact between at least one end of the ring 74 and one side of the oscillating pin 80. That is, the end of the 30 ring 74 is flush with the side wall of the oscillating pin 80 during pumping action and is in a sliding engagement during pumping operation and in stationary engagement therewith when the compressor is in its idle condition. Thus the 35 oscillating ring 74 oscillates within the compression chamber 70 with respect to the axis of the pin 80, and the oscillating pin oscillates with its ends slidably engaging opposite vertical walls of the compression chamber. By this arrangement 40 there is provided two distinct compression spaces, and, also by the present arrangement one compression space is entirely sealed from the other and the intake side of the compressing means is also sealed by the same means from the 45 discharge side.

Referring now to Fig. 4, there is shown a modified form of compressing means. In this modification the oscillating pin 82 is formed in two pieces and is held in engagement with one 50 end of the oscillating ring by means of a spring 83. This arrangement provides a self-adjusting contact between the ring and pin on the discharge side of the compressing means to thus prevent any recompression of gas. Other details 55 shown in this modification correspond to those shown in Fig. 3.

The compressing means 37 is arranged to be actuated by a shaft 85 which is driven by rotor 33 of motor 30. The shaft 85 is journaled on its 60 one end in a bearing 87 which is carried by web 62 and on its opposite end is journaled in a bearing 90 carried by the lower member 54 of the casing 40. The shaft 85 maintains its position within the bearings 87 and 90 by means of 65 gravity, the end of said shaft resting upon a button 95 carried by the lower member 54 of casing 40. The shaft on its upper end is provided with an eccentric portion 100 which carries the ball bearing member 102. The ball bearing member 70 102 engages the disc-shaped member 72 by a slip-fit at 72a to thus engage the ring 74. As shown in the drawings the compression chamber is concentric with the main portion of the shaft 85 while the ring member 74 is concentric with the 75 eccentric portion of shaft 85. Thus it will be

noted that rotation of shaft 85 due to the eccentric arrangement thereon that the ring 74 oscillates within the compression chamber 70 in the manner previously described. In order to counter-balance said eccentric arrangement there is 5 provided counter-balancing means 105 which is carried by shaft 85 diametrically opposite to the eccentric portion of the shaft 85. The counter-balancing means 105 includes a portion 106 above the disc-shaped member 72 and a similar portion 10 107 which is located below said disc-shaped member. As previously stated the disc-shaped member 72 forms the top wall of the compression chamber 70 and as will be noted said disc-shaped member rests upon the web 62 by gravity alone. 15

Means have been provided for sealing the joints between the disc 72 and the web 62 to thus seal the compression chamber so as to enable the compressing means to perform its compressing action. In order to provide means for sealing 20 said joint we employ the lubricant within the reservoir for submerging the compressing means in lubricant. This is accomplished by providing a spiral groove 110 on the lower end of shaft 85. This groove receives lubricant from the reservoir 25 57 through strainer 111 and passage 111a. The groove 110 communicates with a radial bore 112 in shaft 85, which bore leads to a central passage 115. The central passage permits lubricant to flow through the open end at the top of the 30 passage and into the chamber 65. The lubricant thus supplied to the chamber 65 acts to lubricate the compressing means and to seal the joint between the disc-shaped member 72 and the web 62. The central passage 115 in shaft 85 also 35 40 communicates with a radial bore 125 in shaft 85 for supplying lubricant to the bearing 87 while the spiral passage 110 in shaft 85 serves to supply lubricant to bearing 90. The disc-shaped member 72 is provided with a plurality of vertical 45 passages 110a which extend from the top of said disc-shaped member to the underside thereof which is in engagement with the web 62 to thus permit lubricant to flow therethrough to lubricate the joint between the disc and web. In 50 order to lubricate the bottom wall of the compression chamber 70 a plurality of vertical passages 112 have been provided in the disc-shaped member 72 and which extend from the top thereof through the bottom of the oscillating ring 74. A separate passage 113 is provided in disc 72 55 which leads to a plurality of passages 114 formed at right angles to each other in pin 80 to lubricate between the ends of the pin 80 and walls of chamber 70, and between the sides of the pin 80 and the ends of ring 74.

The operation of the compressor is as follows: The gaseous refrigerant, for example CH_2ClF , is withdrawn from the vapor conduit as previously stated and is drawn into the intake chamber 59 which communicates with the pressure chamber 70 through an intake passage 140 which communicates with a passage 142 provided in the ring 74. The passage 142 extends from one side to the other of ring 74 so as to supply fluid to be compressed to each compression space in the compression chamber 70. By this arrangement gaseous refrigerant or the refrigerant from the intake or low pressure side of the receiver is admitted to the compression chamber to be compressed. The compressed refrigerant is then discharged through valves 77 which are covered by a film of lubricant received from the oil pump 110 to thus dampen valve noises. The valves 77 are provided with a cut-away portion 145 75

which tends to form a small reservoir for lubricant adjacent said valve seats. The valves proper are formed of thin reeds which will be flexed during operation of the compressing means and in order to provide a stop for said valves there is provided an angular projection 150. The high pressure gas discharged through the valves 77 is then passed to the high pressure chamber 66 through the ball bearing member 102, which ball bearing member 102 also serves as an overflow drain for lubricant from the chamber 65 to be returned to the reservoir 57. The high pressure gas also passes through conduits 155 before entering the high pressure chamber 66. The high pressure gas passes from the chamber 66 into the condenser 24 as previously stated through a suitable outlet passage 157. In order to protect the windings of the motor there is provided a shield 160 which is carried by the rotor 33 and extends above the lowermost portion of the conduit 155. This shield 160 prevents the oil which is being drained from the chamber 65 to reservoir 57 from splashing upon the windings of the motor and permits same to pass through passages 162 provided in the rotor 33 to the reservoir 57, and since the uppermost portion of the shield 160 is above the lowermost portion of the conduit 155 the shield 160 tends to act as a separator for separating some of the lubricant which may be come entrained with the gas in passing from conduit 155 to outlet 167. However, in the event some lubricant should become entrained with the gas and pass into the chamber 66 on the outside of the shield 160 it is returned to the reservoir 57 by means of one or more passages 167 provided in the stator 35.

In refrigerating apparatus of the type herein described it is customary to operate the compressor intermittently to maintain the evaporator, or the refrigerator cabinet which generally houses the evaporator at a substantially constant temperature. Thus it is customary to start the compressor when the temperature in the refrigerator reaches a predetermined high limit and to stop the compressor when the temperature reaches a predetermined low limit. Since the discharge or high pressure side of the compressor is under condenser pressure and the suction or low pressure side is under evaporator pressure, it is obvious that the compressor whether of the rotary type, oscillating type, the vibrator type or of any other type, start under load and consequently the motor requires a high starting torque unless some means is provided for permitting the motor to reach a running speed before the load is taken up. In order to provide means for loading and unloading the compressing means we have provided the intake chamber 59 and have arranged for the high pressure gas in the chambers 65 and 66 to escape therefrom, during periods of idleness of the compressor, through the compressing means and compression chamber 70 into the intake chamber 59 so as to equalize the pressure within the chambers 59, 65 and 66. This leakage through the pump takes place between the joint of the disc-shaped member and a web member 62 and some leakage occurs through the passages 112 which leads to the bottom wall of the compression chamber 70 from the chamber 65. By this arrangement sufficient high pressure gas will pass into the chamber 59 so as to enable the compression chamber 70 to be supplied with high pressure gas until the motor attains a running speed. This is accomplished by providing an intake chamber of sufficient size to accommo-

date such a quantity of high compressed gas. Thus it will be noted that the compressing means is acting upon high compressed gas and the compressing of low pressure gas into high pressure gas will not take place until the high pressure gas has all been withdrawn from the chamber 59 and low pressure gas is admitted into the compression chamber 70.

The rotation of shaft 85 is clockwise (Figs. 3 and 4) giving the ring 74 a tendency to rotate also clockwise, thus maintaining a contact between its end 74a and pin 80. The plane contact also insures correct oscillation of the pin with the ring.

While the preferred form of the invention includes two compression chambers, it is to be understood that many advantages of the invention may be obtained when only one compression chamber is used, either on the inner or outer periphery of the ring.

While the form of embodiment of the invention as herein disclosed constitutes a preferred form, it is to be understood that other forms might be adopted, all coming within the scope of the claims which follow.

What is claimed is as follows:

1. A compressor for refrigerating apparatus comprising in combination a casing, means providing a chamber within said casing, an oscillating ring disposed in said chamber, means for actuating said ring, said ring together with said first named means providing a compression space adjacent the inner periphery of said ring and providing a compression space adjacent the outer periphery of said ring, and a rocking pin cooperating with said ring for sealing said compression spaces from one another, there being a plane contact between said ring and said pin so as to provide a slidably engagement therebetween, and self-adjusting means for taking up clearance slack for maintaining said contact said self-adjusting means cooperating with said ring and pin.

2. A compressor for refrigerating apparatus comprising in combination a fluid-tight casing, means dividing said casing into a plurality of compartments, a shaft extending through said means, a motor below said means for driving said shaft, an eccentric on said shaft, a ball bearing member carried by the eccentric on said shaft, means forming a compression chamber, and an oscillating ring in said chamber actuated by said bearing member, said compression chamber communicating with one of said compartments and said compartment discharging compressed fluid to a second compartment through said ball bearing member, said casing providing an outlet passage in said latter compartment.

3. A compressor for refrigerating apparatus comprising in combination a drive shaft, an eccentric on said shaft, a ball bearing member carried by the eccentric on said shaft, means forming an annular chamber, a disc-shaped member having a downwardly extending ring oscillated by said eccentric, the disc-shaped member forming the top wall of said chamber and said ring extending into said chamber, said ring together with said chamber forming a plurality of compression spaces during the operation of said disc-shaped member, a pin passing through said ring and having a sealing engagement with said ring to seal said compression spaces from each other and individual outlet check valves for each compression space carried by said disc-shaped member whereby pressure differentials may be established between said compression spaces.

4. A compressor for refrigerating apparatus comprising in combination a member having a flat top portion and having a rectangularly cross-sectioned annular groove in said portion, an oscillator having a flat bottom portion in sealing engagement with said flat top portion and having a downwardly extending ring in sealing contact with both side walls and bottom of said annular groove to form two compression spaces on each side of said ring, means in sealing contact with said member and with said ring forming compression abutments in said compression spaces, means forming a compression chamber above said member, means forming discharge passages from said compression spaces to said compression chamber adjacent said compression abutments, and check valves for said discharge passages.
5. A compressor for refrigerating apparatus comprising in combination a member having a flat top portion and having a rectangularly cross-sectioned annular groove in said portion, an oscillator having a flat bottom portion in sealing engagement with said flat top portion and having a downwardly extending ring in sealing contact with both side walls and bottom of said annular groove to form two compression spaces on each side of said ring, means in sealing contact with said member and with said ring forming compression abutments in said compression spaces, means forming a compression chamber above said member, means forming discharge passages from said compression spaces to said compression chamber adjacent said compression abutments, check valves for said discharge passages and means for maintaining a supply of oil over said check valves.
6. A compressor for refrigerating apparatus comprising in combination a motor driven shaft, an eccentric portion on said shaft, means forming an annular compression chamber, an oscillating ring concentric with said eccentric portion, said ring being located in said chamber and actuated by said eccentric and forming two compression spaces on each side of said ring, means sealing said spaces from each other and oil passages in said ring.
7. A compressor for refrigerating apparatus comprising in combination a motor driven shaft, an eccentric portion on said shaft, means forming an annular compression chamber, an oscillating ring concentric with said eccentric portion, said ring being located in said chamber and actuated by said eccentric and forming two compression spaces on each side of said ring, means sealing said spaces from each other, means for discharging compressed fluid from one edge of the ring and back through the center of said ring.
8. A compressor for refrigerating apparatus comprising a drive shaft, an eccentric on said drive shaft, means forming an annular chamber, a disc-shaped member having a downwardly extending ring oscillated by said eccentric, the disc-shaped member forming the top wall of said chamber and said ring extending into said chamber, said ring together with said chamber forming a compression space during the operation of said disc-shaped member, intake means for said compression space, upwardly directed discharge means from said compression space carried by said disc-shaped member, a check valve on said discharge means, and means to maintain a body of oil on said check valve.
9. A compressor for refrigerating apparatus comprising a drive shaft, an eccentric on said drive shaft, means forming an annular chamber, a horizontally disposed disc-shaped member having a downwardly extending ring oscillated by said eccentric, the disc-shaped member forming the top wall of said chamber and said ring extending into said chamber, said ring together with said chamber forming a compression space during the operation of said disc-shaped member, intake means for said compression space, upwardly directed discharge means in said disc-shaped member from said compression spaces, check valves carried by said disc-shaped member on said discharge means, and means to maintain a body of oil on said check valves.
10. A compressor comprising a drive shaft, an eccentric on said shaft, means forming a vertical cylindrical chamber, means forming a lower horizontal wall for said chamber, means forming an upper horizontal wall for said chamber, a ring oscillated by said eccentric against said vertical cylindrical chamber between said upper and lower horizontal walls, a gas outlet valve on said upper wall, and means for flowing a film of lubricant over said valve.
11. A compressor comprising a drive shaft, an eccentric on said drive shaft, means forming an annular cylindrical chamber having inner and outer coaxial vertical cylindrical walls, means forming a lower horizontal wall for said chamber, means forming an upper horizontal wall for said chamber, a ring having coaxial cylindrical walls oscillated by said eccentric against said inner and outer coaxial vertical cylindrical walls between said upper and lower horizontal walls, a gas outlet valve on said upper wall, and means for flowing a film of lubricant over said valve.
12. A compressor comprising a drive shaft, an eccentric on said shaft, means forming a vertical cylindrical chamber, means forming a lower horizontal wall for said chamber, a plate forming an upper horizontal wall for said chamber, a ring carried by said plate and oscillated by said eccentric against said vertical cylindrical chamber and against said lower horizontal wall, a gas outlet valve on said plate and means for flowing a film of lubricant over said plate.
13. A motor-compressor unit comprising a casing, said casing enclosing a motor and a compressor drivingly connected together, said compressor comprising a drive shaft, an eccentric on said shaft, means forming a vertical cylindrical chamber, means forming a lower horizontal wall for said chamber, a plate forming an upper horizontal wall for said chamber, a ring carried by said plate and oscillated by said eccentric against said vertical cylindrical chamber and against said lower horizontal wall, a gas outlet valve on said plate, a reservoir for a body of lubricant, and means for lubricating said motor from said body of lubricant and for maintaining a film of lubricant over said valve.
14. A motor-compressor unit comprising a casing, said casing enclosing a motor drivingly connected to a compressor comprising a drive shaft, an eccentric on said drive shaft, means forming an annular cylindrical chamber having inner and outer coaxial vertical cylindrical walls, means forming a lower horizontal wall for said chamber, a plate forming an upper horizontal wall for said chamber, a ring carried by said plate having coaxial cylindrical walls oscillated by said eccentric against said inner and outer coaxial vertical cylindrical walls between said upper and lower horizontal walls, a gas outlet valve on said plate, and

- means for maintaining lubricant over said valve and for circulating lubricant to said motor.
15. A compressor for refrigerating apparatus comprising a drive shaft, an eccentric on said drive shaft, means forming an annular chamber, a disc-shaped member having a downwardly extending ring oscillated by said eccentric, the disc-shaped member forming the top wall of said chamber and said ring extending into said chamber, said ring together with said chamber forming a compression space during the operation of said disc-shaped member, intake means for said compression space, upwardly directed discharge means from said compression space carried by said disc-shaped member, a check valve on said discharge means, and means causing the fluid compressed by said compressor to pass through said disc-shaped member after having been discharged through said check valve.
- 20 16. A compressor for refrigerating apparatus comprising a sealed casing divided by a flat plate

having a cylinder formed therein, a disc-shaped piston member oscillating on said plate and cooperating with said cylinder, means for discharging compressed fluid from said cylinder to one side of said disc-shaped member, means for passing 5 said compressed fluid through said disc-shaped member to the other side of said flat plate and an outlet from the casing on the last named side of said flat plate.

17. A compressor having a cylinder, and a piston plate oscillatable with respect to said cylinder, a refrigerant inlet means in the side of said plate, means for discharging gaseous compressed refrigerant on one side of the plate, and then passing the gaseous refrigerant through the center of 15 said compressor to the other side of said plate a casing on said last named side of said plate receiving said gaseous refrigerant, and a gaseous refrigerant outlet in said casing.

HARRY B. HULL.
